UNITED STATES PATENT OFFICE.

JAMES BOYD ANDERSON, OF SHICKSHINNY, PENNSYLVANIA.

MINE-PULLEY.

1,218,505.

Specification of Letters Patent.

Patented Mar. 6, 1917.

Application filed June 2, 1916. Serial No. 101,429.

To all whom it may concern:

Be it known that I, JAMES BOYD ANDERSON, a citizen of the United States, residing at Shickshinny, in the county of Luzerne 5 and State of Pennsylvania, have invented certain new and useful Improvements in Mine-Pulleys, of which the following is a specification.

My invention relates to improvements in 10 pulleys or rollers which may be used for various purposes but are especially adapted for use in supporting the hauling cables attached to mine cars to prevent the cable from chafing or cutting into the ties and 15 also to reduce the drag friction.

Mine pulleys are constructed of hard wood 20 and are provided with a normal iron bearing pin or spindle which is driven through a hole bored through the axis. Owing to 25 the difficulty of boring an axial hole from one end to the other, it is common practice to bore from each end toward the center. As the boring tool has a tendency to follow the grain of the wood, the holes are usually 30 out of alinement with each other and are not parallel with the axis of the roller. Owing to this fact it is with difficulty that the pins are driven through and large numbers are 35 split in attempting to force the pins through the crooked holes. Furthermore these inaccuracies cause the rollers to wobble badly which results in destructive wear upon the 40 bearings.

For the purpose of overcoming the defects 45 above noted, applicant has devised a pulley or roller having separate bearing pins upon either end and which are secured in comparatively shallow holes or sockets which may therefore be accurately bored on 50 the line of the central axis. I have also devised a method of securing the bearing pins so that they may sustain the strains to which 55 they are subjected without endangering the integrity of the pins or loosening them in their sockets.

In the accompanying drawings, Figure 1 60 is a side elevation illustrating the manner of using mine pulleys; Fig. 2 is a top-plan view of a mine pulley or roller embodying 65 my invention; Figs. 3 and 4 are longitudinal sectional views respectively of one end of a pulley having a socket bored therein and showing the manner of inserting the form of 70 bearing pin or gudgeon illustrated in Fig. 7; and Figs. 5 and 6 are longitudinal sec-

tional views of one end of a pulley showing respectively another form of socket and the manner of inserting a bearing pin or gudgeon of the form illustrated in Fig. 8.

Pulleys such as are employed in the 60 tracks used for hauling mine cars are subjected to very hard usage and to great strains which tend to loosen the bearing pins. It is necessary, therefore, to provide means for securely fastening the pins within the 65 body of the pulley or roller. As previously stated, I bore a comparatively short or shallow hole or socket 2, in each end, which can be accurately located on the central axis, thereby insuring a steady even rotation of 70 the body of the roller or pulley. This feature alone eliminates a large proportion of the wear heretofore found in mine pulleys.

When I employ a bearing pin of the form 75 shown in Fig. 7, I bore a comparatively shallow hole 2, of uniform bore into each end of the roller block 3, which is just sufficient in diameter to permit the insertion of the gudgeon pin 4. When the end of the pin bears against the inner end of the hole or 80 recess 2, as indicated in solid lines in Fig. 4, it is then driven by hard blows until the inner split end has cut its way into the solid body of the roller as shown by dotted lines in Fig. 2. For the purpose of causing the 85 inner end of the pin to spread outwardly in the manner indicated, I cut a number of slots 5 in the end and bevel the edge from the inside surface to the periphery as indicated at 4^a. As the tube or pin is driven into 90 the body of the roller, the greater resistance of the wood being cut is exerted against the inner beveled edges 4^a, exerting a great pressure outwardly and causing the metal to spread until it is securely anchored in the 95 manner shown.

I may employ another form of gudgeon pin, shown in Fig. 8, the method of securing it in the roller being illustrated in Figs. 5 and 6.

One end of the pin 4' is threaded as indicated at 4^b. In preparing the holes or recesses in the opposite ends of the roller block 3, I first bore a shallow portion 2^a, as in the method previously described, of a diameter to permit the pin or tube to be inserted with a snug fit. I then bore from the bottom of the hole 2^a, a hole 2^b, slightly less in diameter, amounting usually to a difference of one-eighth of an inch, the dif- 110

ference being less than twice the depth of the threads on the pin.

The pin 4' is inserted in the hole to the depth of the portion 2^a, and is then firmly clamped in a suitable tool and rotated, causing the threads to cut a corresponding spiral in the walls of the recess until the end of the pin has reached the bottom or inner end of the portion 2^b. The threads 10 have thus embedded themselves in the solid wood and formed an anchorage which is capable of resisting an outward pull of several thousand pounds. I have shown the pin in the form of a tube but in this 15 threaded form I may employ a solid pin if desired.

In each form of my invention the inner end of the gudgeon pin is firmly anchored with very great rigidity so that it is able 20 to withstand all of the hard usage to which mine rollers are subjected without becoming loose. I make the recess or hole of such depth that the anchoring part of the pin shall be inserted a sufficient distance to provide 25 a portion of the uncut or unthreaded pin within the recess portion 2 or 2^a, which as previously explained, fits snugly about the periphery of the pin and forms a bearing therefor to brace the pin against lateral 30 or bending strains which are greatest at this point.

My pulleys are usually supported in the manner indicated in Figs. 1 and 2. The pins 4 are mounted in bearings in brackets 35 6, which may conveniently be secured to the ties 7 upon which the rails 8 are spiked. As indicated in Fig. 1, the cable 10, by which the car 12 is hauled, passes over these rollers, which not only prevent the cable

from cutting into the ties but also reduce 40 the drag friction.

While I have described in detail the particular construction shown in the accompanying drawings for the purpose of clearly disclosing embodiments of my invention, I 45 am aware that various changes may be made within the scope of my claims and without in any manner departing from the spirit of my invention.

I claim:—

1. A pulley or roller comprising a wooden body portion provided with recesses in opposite ends and gudgeons extending into said recesses, said gudgeons having main body portions of uniform diameter throughout which fit snugly within the recesses to brace the gudgeons against lateral pressures or strains, and anchoring portions which are embedded in the fibers of the wood. 55

2. A pulley or roller comprising a wooden body portion provided with recesses in opposite ends, and gudgeons extending into said recesses, said recesses having portions of different diameters, the outer portion having the larger diameter, said gudgeons having main body portions of uniform diameter throughout which fit snugly within the outer recess portions to brace the gudgeons against lateral pressures or strains, and anchoring portions which extend into 60 the inner smaller recess portions and are embedded in the fibers of the wood. 65

In testimony whereof I affix my signature in presence of two witnesses:

JAMES BOYD ANDERSON.

Witnesses:

D. J. MEUSCH,
E. W. GARRISON.
